Maxwell C. Frank

UNITED STATES PATENT OFFICE.

MAXWELL C. FRANK, OF PIEDMONT, CALIFORNIA.

ELECTRIC PUSH-BUTTON.

Specification of Letters Patent. Patented Feb. 12, 1918.

1,256,007.

Application filed January 8, 1917. Serial No. 141,207.

To all whom it may concern:

Be it known that I, MAXWELL C. FRANK, a citizen of the United States, residing at Piedmont, in the county of Alameda and State of California, have invented certain new and useful Improvements in Electric Push-Buttons, of which the following is a specification.

My invention relates generally to luminous devices, rendered so, by the application of luminous compositions, and in particular relates to electric push buttons illuminated by such agents.

The primary object of this invention is to provide self luminous means for the push button, so that it can be readily seen and located in the dark, wholly without other indicating means. With this and other objects in view, my invention consists of a pair of mounted electric switch terminals housed within a casing, together with the push button center, which is recessed and made luminous and which constitutes the main part of my invention.

In the accompanying sheet of drawings, the invention is illustrated, in which—

Figure 1 is a plan view of the push button, and Fig. 2 a side view showing it attached to a wall; the push button center is protruding.

Fig. 3 is a sectional elevation of the push button of Fig. 1 taken centrally; the terminals and terminal base being shown in full.

Fig. 4 is an enlarged sectional elevation of the push button center, showing the luminous material and a hollow core retaining it therein.

Fig. 5 is a cross-section of a modification, showing the luminous material at the inner top only, and the hollow retaining core.

Similar numerals of reference indicate corresponding parts in all the figures, in which—

1 is the casing of the push button provided with an out-flaring stand and a top central aperture, which has its circumferential edge turned inwardly forming a shoulder. Housed within the casing are the mounted electric switch terminals 2. 3 is the push button center shown in the form of a shell provided with a basal flange 4, and said center in Fig. 3 is shown in its normal position, the upper face of said basal flange bearing against the shoulder of the casing 1, and held in this position by the upper

switch terminal 2, pressing against the bottom bearing face of said flange 4.

On depressing the push button center, the upper bearing face of the basal flange dis- 60 contacts from the casing shoulder, and the upper electric switch terminal contacts the lower one, and while in this depressed position the electric circuit is completed and in 65 service.

The push button center 3 shown enlarged in Fig. 4, consists of luminous material within a recess of preferably, an integral structure of glass or other suitable substance, comprising a round, hollow body 70 portion provided with a closed top and a concentric basal flange 4. 5 is the luminous material covering a comparatively large area, and in this form of push button center may be of low-grade in quality, and may be 75 held in contact with the surface of the recess by the hollow binding core 6, which is shown in capsule form and which is made of any suitable material such as thin metal. This hollow binding core is made a little 80 larger in diameter at its open end than at its closed end, so that when it is inserted and pressed into seating position within the recess, it will bear and bind against the surface and by virtue of its enlarged diameter 85 and reacting force, be retained therein. In some cases I may further wish to secure the core or the luminous material to the recess, this may be accomplished by applying to the open end of the core, and the exposed 90 luminous material and the exposed surface of the recess, an adhering substance 7 such as gum arabic for example, which not only secures the luminous material in position, but also forms at the same time a hermeti- 95 cal and protecting seal for the said luminous material. The latter material after a lapse of about five years dries out, and has a tendency to pulverize and flake off from any surface, so it is essential for efficiency and durability that it always be kept in close contact with the surface and sealed and protected.

In Fig. 5 the push button center is of similar shape to that of Fig. 4, with the exception of the top which differs from the uniform thickness concavo-convex lens top of the latter figure, by being provided with a plano-convex top, the surface of which may be composed of polygons as shown in 110 the cross-section by the straight lines; also the walls of the body are made thicker,

thus decreasing the diameter of the recess. This reduction in diameter is done for the purpose of using a comparatively small quantity of a higher grade of luminous material, and allowing the magnifying power of the lens top to disseminate the luminous rays, thus making the actual area of the luminous material appear much larger. This form of lens magnifies larger than the 10 parallel-curved lens top of Fig. 4.

Having described my invention and an embodiment of it, it is to be understood that the same covers other variations, which come within the spirit of the invention and 15 which are within the scope of the claims, therefore, being aware that prior to my invention, push buttons have been made luminous in various ways, I do not claim broadly such; but what I claim is—

20 1. A push button comprising a casing housing a pair of electric switch terminals, a terminal base and a transparent, homogeneous, self-luminous open shell, push button center; said luminous shell provided 25 with a basal bearing flange around said open end engaging its casing and said terminals.

2. A push button center comprising a round, hollow, transparent body provided 30 with a closed end and an open end, a basal flange around said open end, luminous material within said body and held in contact thereto by a binding core, and said core further secured to the body by an adhesive, said 35 adhesive also forming a hermetical seal between the core and said body.

3. A push button center comprising a round, hollow, transparent body provided

with a closed end and an open end, a basal flange around said open end, luminous coating 40 within said body and held in contact thereto by a binding core.

4. A push button center comprising a round, hollow, transparent body provided with a closed end and an open end, a basal 45 flange around said open end, luminous material within said body, and an adhesive coating hermetically sealing the luminous material within said body.

5. In a push button, an integral structure 50 of glass, comprising a hollow body portion, a lens top portion, and a flanged bottom portion, luminous material within said integral structure and a hollow binding core pressed within said body to retain said 55 luminous material therein.

6. In a push button, an integral structure of glass comprising a hollow body portion, a lens top portion and a flanged bottom portion, luminous material in said integral 60 structure and an adhesive coating applied thereto forming a hermetical seal for the luminous material within said body.

7. In a push button, a cylindrical, recessed, flanged, integral structure of glass, 65 the closed end of which is formed into a plano-convex lens to cause to subtend a larger visual angle for the luminous coating within said recess.

In testimony whereof I have affixed my 70 signature, in the presence of two witnesses, this 2nd day of January, 1917.

MAXWELL C. FRANK.

Witnesses:

LEROY W. JACKSON,
LAURA F. FRANK.

It is hereby certified that in Letters Patent No. 1,256,007, granted February 12, 1918, upon the application of Maxwell C. Frank, of Piedmont, California, for an improvement in "Electric Push-Buttons," errors appear in the printed specification requiring correction as follows: Page 2, line 25, claim 1, for the word "said" read *its*; same page and claim, line 26, for the word "its" read *said*; and that the said Letters Patent should be read with these corrections therein that the same may conform to the record of the case in the Patent Office.

Signed and sealed this 2d day of April, A. D., 1918.

[SEAL.]

J. T. NEWTON,

Acting Commissioner of Patents.
